The ornamental design for pants, as shown and described.

DESCRIPTION

This application is also a reissue of Design Pat. No. D654, 661, which issued from Design patent application Ser. No. 29/396,448.

Notice: More than one reissue application has been filed for the reissue of U.S. Design Pat. No. D654,661. The reissue applications are divisional reissue application Ser. No. 29/559,022 (the present application), divisional reissue application Ser. No. 29/518,388, and reissue application Ser. No. 29/483,494, all of which are reissues of U.S. Design Pat. No. D654,661.

FIG. 1 is a front view of pants according to [a first embodiment of] the design;

FIG. 2 is a rear view thereof;

FIG. 3 is a right side view thereof;

FIG. 4 is a left side view thereof; and,

FIG. 5 is a front perspective view thereof;

FIG. 6 is a rear view of pants according to a second embodiment of the design, the front, left side, and front perspective views being the same as FIGS. 1 and 4-5, respectively; and,

FIG. 7 is a right side view thereof.

The symbol depicted in FIGS. 6-7 forming part of the claimed design is a registered trademark of Lululemon Athletica Canada Inc.]

The broken lines shown in FIGS. 1-5 illustrate portions of the pants that form no part of the claimed design.
